Fig. 4

FIG. 1 is a perspective view of the table showing my new design;

FIG. 2 is a plan view thereof;

FIG. 3 is a side elevational view of my ornamental table; and

FIG. 4 is an end elevational view thereof.

My design is characterized by a table top having an opening formed therein covered by a transparent panel having an ornament mounted off-center of said panel and a shelf of the same configuration as said table top but of smaller size positioned below said table top and secured by connector pins extending from the legs of the table to the said shelf, all as shown.

I claim:

The ornamental design for a table, substantially as shown and described.
